(57) **CLAIM**

The ornamental design for a car, toy car replica and/or other replica, as shown and described.

DESCRIPTION

FIG. 1 is a top, front and left side perspective view of a car, toy car replica and/or other replica showing our new design; FIG. 2 is a top, rear and right side perspective view thereof; FIG. 3 is a right side elevation view thereof; FIG. 4 is a left side elevation view thereof; FIG. 5 is a front elevation view thereof; FIG. 6 is a rear elevation view thereof; and, FIG. 7 is a top plan view thereof.

The portions of the vehicle shown in broken lines are for environmental and illustrative purposes only and form no part of the claimed design.
